UNITED STATES PATENT OFFICE

OSCAR A. DAHLBERG, OF MINNEAPOLIS, MINNESOTA, ASSIGNOR TO JOSEPH SUNNEN,
OF KIRKWOOD, MISSOURI

METHOD OF REFINISHING ENGINE CYLINDERS

Application filed June 10, 1932. Serial No. 616,411.

My invention has relation to improvements in methods of refinishing engine cylinders and devices therefor and it consists in the novel features and principles of construction more fully set forth in the specification and pointed out in the claims.

My improved method consists in refinishing worn engine cylinders that are either badly scored, or out of round, or both, and it comprises a series of operations including the grinding of the cylinder wall with suitable abrasive elements having a rough surface for the first grinding, or rough grinding operation, followed by one or more fine grinding operations in which abrasive elements having successively finer grinding surfaces are used, after which a burnishing operation is employed. This latter operation consists in scouring or burnishing the cylinder wall by means of a burnishing brush or a set of brushes mounted in the same or similar holder which was used in the abrading or grinding operations.

The invention includes the burnishing device or brush with which the finer finishing operation on the cylinder is performed. Grinding stones, or hones, operate, as is well known, by abrasion, and when a cylinder is reconditioned by grinding, sharp abrasion scores remain on the wall of the cylinder, even though a relatively fine stone is used for the final grinding operation. If the cylinder is true these scores are tolerated because they are uniformly distributed over the entire cylinder wall. However, the presence of the abrasion marks prevents a newly ground cylinder from functioning at its maximum efficiency until after it has been operated a certain length of time, or worn in. Of course, during this "wearing in", or smoothing operation, excessive wear comes on the piston rings so that they are seriously damaged by the time the cylinder wall has been worn smooth.

My invention obviates to a large extent the necessity of "wearing in" the cylinder by use, as it provides means for wearing off the sharp edges of the abrasion marks, and thus burnishing the cylinder wall as a final, or finishing step, in the reconditioning of worn

and out of round cylinders. After reground cylinders have been burnished with my improved device they are smooth, and require very little "wearing in". Obviously, the piston rings are thus subjected to no more than normal wear when first operated in a reground cylinder and will function efficiently for a longer time than otherwise.

It is a further object of the invention to provide a burnishing brush that may be substituted for the abrasive element in a "Sunnen" cylinder grinder of the type shown in the co-pending application of Joseph Sunnen, Serial No. 233,788, filed November 17, 1927, so that a single holder will suffice for performing both the grinding and burnishing operations. Further and other advantages will be better apparent from a detailed description of the invention in connection with the accompanying drawing, in which:

Figure 1 is a side elevation of my improved burnishing device with parts of the brush holder and parts of one of the brushes broken away; Fig. 2 is a horizontal cross-section of the device taken on the zigzag line 2-2 of Fig. 1; Fig. 3 is a longitudinal section through the brush taken on the line 3-3 of Fig. 1; Fig. 4 is a greatly enlarged cross-section through a fragment of cylinder wall showing the abrasion marks on the inner surface thereof before the cylinder wall has been burnished by my improved device; and Fig. 5 is an enlarged cross-section through the same cylinder wall portion after the said cylinder wall has been burnished.

Referring to the drawing, 1 represents the tool holder of a Sunnen cylinder grinder of the type described in the above referred to patent application, said holder being suspended by yoke 2 and collar 3 from a shaft 4. The collar 3 is pivotally connected to the holder 1 by means of studs 5, 5 and the yoke 2 is pivotally connected to the collar by means of studs 6, 6 so that a universal joint connection is formed between the shaft 4 and the holder 1. The holder 1 is provided with a longitudinally disposed axial bore 7 within which is housed a pinion shaft 8 rotatable by means of the adjusting head 9 for the purpose of extending and retracting the brushes

10, 10. The construction and the operation of the tool holder, comprising the parts just described, is substantially the same as that of the holder of the honing device described 5 in detail in the aforesaid patent application and will not be further described herein except insofar as necessary to explain the operation of the burnishing elements, or brushes 10, 10.

10 Each of the brushes 10 comprises a body portion 11 from the back of which toothed pins or rack bars 12, 12 project, said rack bars supporting the brush in the holder 1 by virtue of spaced openings 13, 13 (there being a pair of such openings for each brush) in which the rack bars are mounted. It will be observed that openings 13 intersect the bore 7 and the teeth of pinion 8 project into each of said openings 13 so that they will mesh with the teeth t of each rack bar 12, whereby the rack bars are simultaneously moved inwardly or outwardly with the rotation of the pinion 8 so as to effect uniform adjustment of the brushes to fit the cylinder C 25 within which they are being operated. The mounting of the brushes and the method of adjusting the same is the same as that employed when abrasive elements are used, as described in the application referred to, and in practice the brushes are constructed so that they will be interchangeable with the abrasive elements. Thus a mechanic need have but a single holder with his set of grinding tools, or abrasive elements, and burnishing elements. After he has performed the rough grinding operation upon a cylinder, followed up by the smooth grinding operation he replaces the grinding elements with the burnishing elements, or brushes 10, whereupon the burnishing operation is performed in exactly the same manner that the grinding operations were performed.

45 The specific manner of constructing the brush is immaterial, although I illustrate a construction that is durable and otherwise satisfactory. The brush body 11 is provided with side walls 14, 14 bent inwardly so as to form a channel in which a block 15 is inserted, said block being held securely therein by means of screws 16, 16 passed through threaded openings 17, 17 in the brush body 11 and into said block 15. The block 15 carries wire bristle tufts 18, said tufts being held therein in any suitable manner and being sufficiently close together so that the ends of the bristles will merge together so as to form a compact burnishing surface.

55 In refinishing worn engine cylinders the tool holder 1 is first equipped with abrading elements instead of burnishing elements, said abrading elements having a rough finish so as to reduce the cylinder wall rapidly to a correct shape, after which, as heretofore pointed out, these rough grinding elements

are replaced by a grinder having a less severe abrading effect so as to smooth off the roughness left by the rough grinder. However, as long as an abrading element is used on the cylinder wall there will be abrasive 70 scores with sharp edges which would have to be smoothed out by the operation of the engine unless some other means are used to perform this smoothing operation. I have discovered that these abrasion scores may be 75 reduced and smoothed by my improved device. It is apparent that when four brushes are mounted in a holder (as shown in Fig. 2) and are rapidly rotated over the inner surface of cylinder C they will not only scrub the wall of said cylinder to clean it of all loose adhering particles of grindings, but the stiff bristles will also remove all burrs that remain from the grinding operation and round off the sharp abrasive marks, such 80 as shown in Fig. 4, so that such abrasive marks will more or less assume the contour shown in Figure 5. That these sharp abrasive marks are actually worn off is apparent 85 by a microscopic inspection of the cylinder 90 surface. The smoothness of the cylinder wall after burnishing the same with my improved burnishing device is also apparent to the touch when said cylinder wall is carefully felt both before the finishing operation and after the finishing operation. 95

Having described my invention, I claim:

1. The method of refinishing engine cylinders which comprises performing a grinding operation on the cylinder wall with an 100 abrasive element, performing a second grinding operation with an abrasive element of greater fineness than the first, and finally burnishing said wall with a suitable brush.

2. The method of finishing engine cylinders which comprises rapidly rotating a stiff wire brush in contact with the cylinder wall to remove loose adhering particles therefrom, moving said brush into more intimate 105 contact with the wall and continuing said rotation to burnish said wall.

3. The method of refinishing engine cylinders which comprises performing a grinding operation on the cylinder wall with an abrasive element and thereafter moving a wire brush over said cylinder wall with sufficient pressure to burnish the same. 115

4. The method of refinishing engine cylinders which comprises performing a grinding operation on a cylinder wall with an abrasive element, then rapidly rotating a stiff wire brush in contact with the cylinder wall to remove loose adhering particles, and finally moving said brush into more intimate contact with the wall and continuing said rotation to burnish said wall. 120

65 In testimony whereof I hereunto affix my signature.

OSCAR A. DAHLBERG.
